UNITED STATES PATENT OFFICE

2,518,839

EMERGENCY FIRE ESCAPE LADDER

Paul Thonney, Dixie, Wash.

Application June 27, 1947, Serial No. 757,459

2 Claims. (Cl. 228—10)

1

This invention relates to a flexible ladder capable of being readily stored in a compact manner preferably in rooms of upper stories of dwellings adjacent windows and in locations where a likelihood exists of isolation from escape by means, such as stairways and fire escapes.

More particularly, it is an object of the present invention to provide a flexible ladder capable of being readily rolled up to compact form and having means at one end thereof capable of being readily attached to a window sill, porch railing, post or substantial item of furniture for securing said end quickly and easily as the anchored upper end of the ladder and so that the opposite end thereof, may be dropped from the window to the ground below to afford a safe means of escape.

Still another object of the invention is to provide a reel or spool on which the flexible ladder is adapted to be normally wound and which will afford effective means for conveying one end of the ladder to the ground below when dropped from an upper story of enclosures and which will effectively be conveyed by gravity over slanting roofs or other surfaces on which the flexible ladder might otherwise lodge.

Still a further object of the invention is to provide a ladder having flexible side rails, preferably formed of rope and including novel construction of rungs connected to corresponding portions of said flexible side rails and which are effectively anchored thereto by an extremely simple and efficient means enabling the ladder to be economically manufactured and quickly and easily assembled so as to minimize the cost of the completed ladder.

Various other objects and advantages of the invention will hereinafter become more fully apparent from the following description of the drawings, illustrating a preferred embodiment thereof, and wherein—

Figure 1 is a side elevational view showing the emergency fire escape ladder in an applied position;

Figure 2 is a fragmentary front elevational view showing the ladder extended;

Figure 3 is an enlarged cross sectional view taken substantially along a plane as indicated by the line 3—3 of Figure 2;

Figure 4 is an enlarged longitudinal sectional view taken substantially along a plane as indicated by the line 4—4 of Figure 3, and

Figure 5 is an enlarged side elevational view of a portion of the ladder, looking from right to left of Figure 4.

2

Referring more specifically to the drawing, the emergency fire escape ladder in its entirety is designated generally 6 and includes two flexible side rails 7 and 8, which may be formed of corresponding lengths of rope or which may be, as illustrated, formed by corresponding end portions of a single length of rope which is turned back upon itself, intermediate of its ends.

At a point nearly intermediate of the ends of 10 the rope, forming the flexible or rope rails 7 and 8, said rope is fastened to the eye 9 on the shank end of a relatively short hook 10 by the knots 11 to form a loop 12 of the intermediate portion of the rope.

15 The terminal portions of the two ends of the rope, forming the rails 7 and 8, are secured around the hub of a spool 13, as indicated at 13. The spool 12 may assume any desired form, preferably comprising corresponding end members 14, 20 each composed of a pair of bars 15 secured in crossed relationship and which end portions 14 are connected in spaced relationship by the spool hub 16, comprising, preferably, four bars or rods which are fastened adjacent their ends in the 25 apexes or bight portions formed by the crossed arms 15, as best illustrated in Figure 1.

The ladder 6 also includes a plurality of longitudinally spaced, transversely extending rungs 17, each comprising a substantially rigid tube 18, as best seen in Figure 3, having a rod 19 extending longitudinally therein and which is provided with turned back ends forming hooks 20. The rod 19 is of such a length that the curved portions of the hooks 20 thereof are spaced from 30 one another a distance approximately equal to or slightly less than the length of the tube 18, so that said rod 19, including its hooks 20, can be substantially entirely nested within the tube 18. Any number of such rungs 17 may be employed 35 as a part of the ladder 6, depending upon the length thereof, and it will be readily apparent that the ladder is capable of being readily assembled by the simple expediency of extending one end of the rod 19 of each rung, outwardly of 40 an end of its tube 18 and engaging the hook portion thereof with one of the flexible rails 7 or 8. Said end is then forced back into the tube a sufficient distance to expose the other hook 20 at the opposite end of the tube 18, and so that the other rope section or rail 7 or 8 can be engaged therewith, after which the rod 19 is returned to an intermediate position. With each of the rungs 17 45 thus connected in longitudinally spaced relationship to the rope portions 7 and 8, it will be readily apparent that the complete ladder will be assem-

50

55

bled and by correct positioning of the rungs 17, said rungs will be disposed transversely of the rope portions 7 and 8. The hooks 20 will co-operate with the ends of the tube 18 for clamping the rope portions engaged thereby to prevent the rungs 17 from slipping relatively to the ladder sides or rails 7 and 8.

Assuming that the ladder 6 is wound upon the spool 14, the normal position thereof, when not in use to form a compact unit, in case of necessity to accomplish an emergency exit from an upper story of an encloser, a wall of which is indicated at 21 in Figure 1, the hook 10, which is disposed outermost of the wound ladder 6 on the spool 14, can be engaged over the sill 22 of a window opening 23 of said wall 21, after which the spool 14 can be thrown out of the window opening 23 to fall onto the ground 24 below. Occupants of the enclosure may then make their exit through the window 23 and climb down the ladder 6 to the ground 24 below.

The short hook 10 may be readily engaged around the sill 22 and the flexible ladder rail portions 7 and 8, adjacent to the hook, will readily adjust themselves over the bottom portion of the window opening, thus enabling the hook to be quickly and easily applied with the minimum of time loss, and also enabling the ladder and hook to adjust themselves, so that the rungs 17 thereof will all be level. It will likewise be readily apparent that the hook 10 could be attached to a porch rail or other available anchoring means. The loop 12 is provided to enable the ladder 6 to be anchored to a post or other anchoring means, too large to be engaged by the hook 10 and which could be readily accomplished by passing the loop 12 therearound and engaging it with the hook 10.

The spool 14 in addition to affording a means for storing the ladder 6, when not in use, also performs the additional function of providing a means for conveying the ladder to the ground, especially when the ladder is thrown from a window or other opening above a porch or inclined roof, due to the fact that the spool 14 will be conveyed by gravity over such inclined obstructions to the ground below where the ladder alone might become lodged and not fall completely to the ground.

Various modifications and changes are contemplated and may obviously be resorted to, without departing from the spirit or scope of the invention as hereinafter defined by the appended claims.

I claim as my invention:

1. In a flexible ladder of the character described, in combination with a pair of ladder rails formed of rope or other flexible members, a plurality of rungs, each of said rungs comprising an elongated, substantially rigid tube, a rod extending loosely through the tube and having turned back ends forming hooks disposed slidably within the tube, said rod being slideable relatively to the tube for ejecting one of the hooks therefrom for engagement with one of said rails and being slideable in the opposite direction thereafter for exposing the other hook for engagement with a corresponding portion of the other rail, said tube being of a length at least equal to the distance between the remote portions of the hooks, and said hooks, when disposed within said tube and in engagement with corresponding portions of said rails, combining with the tube ends for clamping the rung to said rails.

2. In combination with two elongated flexible members or lengths of rope forming ladder rails or sides, a plurality of ladder rungs, each of said ladder rungs including a rigid tube having hook members disposed therein, one adjacent each end thereof and slideable with respect thereto, means connecting said hook members, the combined length of the hook members and said means being no greater than the length of the tube, and said hook members each being adapted to engage a corresponding portion of a different ladder rail for positioning the rung therebetween and for combining with the adjacent tube end for clamping the rung thereto.

PAUL THONNEY.
